UNITED STATES PATENT OFFICE.

JOHN CAMPBELL, OF LONDON, ENGLAND, ASSIGNOR TO HORNER BROTHERS, OF PHILADELPHIA, PENNSYLVANIA.

DESIGN FOR A CARPET.

SPECIFICATION forming part of Design No. 13,266, dated August 22, 1882.

Application filed July 28, 1882. Term of patent 3½ years.

To all whom it may concern:

Be it known that I, JOHN CAMPBELL, of London, England, have invented and produced a new and original Design for Carpets, of which the following is a specification.

5 The nature of my design is fully represented in the accompanying photographic illustration, to which reference is made.

I claim as my invention—

The design for a carpet, as shown.

JOHN CAMPBELL.
